UNITED STATES PATENT OFFICE.

HARRY STILLSON HART, OF CHICAGO, ILLINOIS, ASSIGNEE TO THE RODGER
BALLAST CAR COMPANY, A CORPORATION OF ILLINOIS.

DUMP-CAR.

SPECIFICATION forming part of Letters Patent No. 739,863, dated September 29, 1903.

Application filed September 8, 1902. Serial No. 122,524. (No model.)

To all whom it may concern:

Be it known that I, HARRY STILLSON HART, a citizen of the United States, residing at Chicago, in the county of Cook and State of Illinois, have invented certain new and useful Improvements in Dump-Cars, of which the following is a specification.

My invention relates to that class of dumping-cars having a frame consisting of upright side and end portions and a rigid bottom portion and having dumping-doors arranged at the bottom thereof, such doors being provided with means for opening and closing them, means for stopping them in any desired position, and means for regulating the speed at which they are permitted to open.

It relates, further and particularly, to the means for opening and closing the dumping-doors and regulating the speed at which they are permitted to open.

The principal object of my invention is to provide a simple, economical, and efficient dumping-car having a frame portion consisting of upright end and side walls, a rigid bottom portion having swinging dumping-doors provided with shaft and chain mechanism for closing such doors and permitting them to open when desired, and means for regulating the speed at which such doors are permitted to open.

My invention consists principally in a dumping-car having a frame consisting of upright side and end portions and having a rigid bottom portion, swinging dumping-doors for such frame, shaft and chain mechanism for closing such doors and permitting them to open, and means for regulating the opening thereof.

It consists, further, in a car provided with a frame having hinged dumping-doors, shaft and chain mechanism for closing such doors and permitting them to open, ratchet-wheel and winding-lever mechanism for such shafts, and detent mechanism consisting of a friction-wheel for each shaft, a metallic friction-strap arranged in contact with such friction-wheel, and means for tightening and loosening such friction-strap, and thereby regulating the speed at which the dumping-door is permitted to open.

In the accompanying drawings, Figure 1 is

a broken side elevation of a dumping-car constructed in accordance with my improvements; Fig. 2, a sectional end elevation taken on line 2 of Fig. 1 looking in the direction of the arrow; Fig. 3, a perspective view of a corner of a car, showing the winding-lever and detent mechanism; and Fig. 4, a sectional plan view of the winding-lever and detent mechanism and one end of a winding-shaft, taken on line 4 of Fig. 1.

In constructing a car in accordance with my improvements I provide a main frame *a*, consisting of side frames *b*, end frame *c*, and rigid A-shaped bottom portions *d* and *e*, resting upon longitudinal sills *f*, transverse sills *g*, tie-beams *h*, and tie-rods *i*. Swinging dumping-doors *j* are mounted, preferably, upon the longitudinal sills *f* by means of hinges *k* and adapted to assume horizontal position when closed and swing downward to permit the load to be dumped. In order to provide suitable means for closing such doors, holding them in closed position, and permitting them to open, winding-shafts *l* are provided, having chains *m* mounted thereon and attached to the swinging sides of the dumping-doors by means of eyebolts *n* and nuts *o*. On one end of each of such shafts is mounted a ratchet-wheel *p*, having a pawl *q* pivotally mounted adjacent thereto, preferably upon corner-plate *r* of the car, by means of a pivot *s*, such pawl being adapted to swing downward into contact and upward out of contact with the ratchet-wheel. A winding-lever *t* is rotatably mounted upon the shaft adjacent to the ratchet-wheel and is provided with a pawl *u*, pivotally mounted thereon by means of a pivot *v* and adapted to swing into and out of contact with the teeth *w* of the ratchet-wheel.

In order to provide suitable means for regulating and controlling the speed at which the dumping-door is permitted to open, and thereby prevent such door from slamming to the detriment and injury thereof and to the injury of the car, and to effect the dumping of the load at a greater or less distance from the center of the car, as desired, a friction-wheel 1 is mounted upon the shouldered end 2 of the shaft by means of an axial perforation 3, adapted to fit upon the shouldered end of

such shaft and hold the friction-wheel in positive relation thereto. A friction-strap 4 is attached at one end to the frame of the car by means of bolts 5 and is held at a suitable 5 distance from the surface of the car by means of rests 6. This friction-strap is wound at least partially around the friction-wheel in contact therewith, and a detent-lever 7 is pivotally attached to the movable end of the 10 strap by means of a pivot 8 and to the fixed end thereof by means of a pivot 9. This detent-lever is split at one end into two parts 10 and 11, which straddle the respective ends of the friction-strap and assist in holding it 15 in place in relation to the friction-wheel.

The friction-strap is made, preferably, of spring metal and is twisted near each end so that the side surfaces of the end portions extend in line with each other and are at right 20 angles to those of the central friction portion, which contacts the friction-wheel, and the arm 12 of the detent-lever is extended beyond the movable end of such strap a sufficient distance to provide the desired fulcrum. 25

By this arrangement it will be readily seen that the closing of the door of the car may be accomplished either by throwing the pawl q into contact with the ratchet-wheel and operating winding-lever with its pawl also in 30 contact with the ratchet-wheel or by operating the winding-lever with the pawl q out of contact with the ratchet-wheel, using the detent-lever and friction mechanism to hold the shaft during the reverse motion of the 35 winding-lever. The door is held in closed position by throwing the pawl q into contact with the ratchet-wheel and is permitted to open by throwing such pawl out of contact therewith. The speed at which the door is 40 permitted to open may be retarded when desired by pressure upon the detent-lever, thereby increasing the friction between the strap and friction-wheel.

The door may be stopped at any desired 45 point by first pressing the detent-lever sufficiently to retard the speed of rotation of the shaft and then throwing the pawl into contact with the ratchet-wheel. The unnecessary strain upon the parts which would follow the throwing of the locking-pawl into locking position without first retarding the speed of the shaft is thus easily avoided by means of the friction-wheel and detent-lever mechanism, as is also the unnecessary strain 50 upon the door and hinges.

I claim—

1. In a dumping-car, the combination of a car-frame, a dumping-door, a rotatable shaft provided with means for connecting it with 55 the dumping-door, means for rotating the shaft, a friction-wheel mounted upon the shaft and rotatable therewith, and a friction-strap in engagement with such friction-wheel, substantially as described.
2. In a dumping-car, the combination of a car-frame, a dumping-door, a winding-shaft

provided with chain mechanism connected with the dumping-door, a ratchet-wheel mounted upon such shaft, a friction-wheel mounted upon the winding-shaft and rotatable therewith, a friction-strap arranged in contact with the friction-wheel, a detent-lever for such friction-strap, and a winding-lever rotatably mounted upon the winding-shaft between the friction-wheel and ratchet-wheel and provided with a pawl adapted to engage the ratchet-wheel, substantially as described. 75

3. In a dumping-car, the combination of a car-frame, a plurality of dumping-doors, a winding-shaft for each of such dumping-doors provided with chain mechanism wound thereon and connected with the dumping-doors, a ratchet-wheel mounted upon the end of such shaft and rotatable therewith, a friction-wheel also mounted upon and rotatable with the winding-shaft, a metallic strap arranged in contact with the friction-wheel and wound partially around such wheel, and a detent-lever connected with such strap for 90 operating it, substantially as described.

4. In a dumping-car, the combination of a car-frame, a pair of dumping-doors, a winding-shaft for each of such doors provided with chain mechanism wound upon such shaft and 95 connected with the dumping-doors, a ratchet-wheel and a friction-wheel upon one end of each shaft, a stopping-pawl mounted adjacent to and adapted to engage the ratchet-wheel, a winding-lever mounted between the 100 ratchet-wheel and friction-wheel and provided with a pawl adapted to engage the ratchet-wheel, a metallic friction-strap mounted upon the car-frame in contact with and wound partially around the friction-wheel, and a detent-lever pivotally connected 105 with both ends of such friction-strap, substantially as described.

5. In a dumping-car, the combination of a car-frame, a plurality of dumping-doors, a 110 winding-shaft for each dumping-door provided with chain mechanism wound thereon and in connection with the dumping-doors, a ratchet-wheel and a friction-wheel upon such shaft, a stopping-pawl mounted upon 115 the car-frame adjacent to and adapted to engage the ratchet-wheel, a winding-lever rotatably mounted upon the winding-shaft between the ratchet-wheel and friction-wheel provided with a pawl adapted to engage the 120 ratchet-wheel, a friction-strap arranged in contact with the friction-wheel and having one end attached to the car-frame, and a detent-lever pivotally mounted upon the fixed 125 end of such friction-shaft and pivotally connected with the opposite end thereof, substantially as described.
